COMBINED FLOWER AND CANDLE HOLDER

Henry Hulthen, Drottninggatan 33, Helsingborg, Sweden

Filed Apr. 26, 1972, Ser. No. 247,908

Claims priority, application Sweden Oct. 27, 1971

Term of patent 14 years

Int. Cl. D11—99; D26—04

U.S. Cl. D35—3 R

FIG. 1

FIG. 3

FIG. 1 is a perspective view of a combined flower and candle holder with the central portion removed for clarity of illustration;

FIG. 2 is a top plan view of the combined flower and candle holder shown in FIG. 1; and

FIG. 3 is a side elevational view of the combined flower and candle holder shown in FIG. 2.

I claim:

The ornamental design for a combined flower and candle holder, as shown and described.
